[57] CLAIM

The ornamental design for a web adjuster, as shown and described.

DESCRIPTION

FIG. 1 is a top plan view of a web adjuster, showing our new design;

FIG. 2 is a bottom plan view thereof, with the lever omitted for clarity of illustration;

FIG. 3 is a front elevational view;

FIG. 4 is a rear elevational view;

FIG. 5 is a right side elevational view;

FIG. 6 is a left side elevational view; and,

FIG. 7 is a sectional view taken on line 7—7 of FIG. 1.
